RATIO CHANGER

Clinton L. Cummings, Natick, Mass., assignor to Barry Controls Incorporated, Watertown, Mass., a corporation of Massachusetts

Application August 22, 1951, Serial No. 243,030

6 Claims. (Cl. 74—354)

This invention relates to ratio changers particularly well suited for use when space and weight factors are critical limitations.

While the invention is adapted for many other uses, its novel features and advantages may be most readily understood by reference to recorders where it is usually desirable to provide means to vary the speed of the tape relative to the recording instrument. The conventional ratio changers employed for such purposes require the removal of nuts or screws to enable the change of ratios to be effected. This makes ratio changing difficult and time consuming since the use of both hands is required.

In accordance with the invention, first and second interconnected coaxial gears of different diameters are supported for movement along an arcuate pathway concentric with a first gear with which the first of the coaxial gears meshes. This enables the first coaxial gear to remain in mesh with the first gear as the second coaxial gear is moved, as required by its diameter, towards or away from the gear with which it is to mesh. Of the two coaxial gears, at least the second is adapted to be quickly and easily removed and replaced. Because of the pathway along which the coaxial gears may move, a gear train may provide a suitable range of gear ratio changes as it is possible to employ any one of a set of gears of different diameters as an intermediate gear.

Ratio changes in accordance with the invention meet such general requirements as compactness, lightness in weight and simplicity of construction. Ease and accuracy in establishing different ratios are assured since only a single gear or single gear unit needs to be removed and replaced to effect a ratio change and such may be done with one hand simply and quickly.

In the accompanying drawings, an embodiment of the invention is shown that illustrates these and other of its novel features and advantages.

In the drawings:

Fig. 1 is a view, in elevation, of a ratio changer employing a replaceable intermediate gear of one diameter,

Figs. 2, 3 and 4 are sections taken along the indicated lines 2—2, 3—3, and 4—4, respectively, of Fig. 1,

Fig. 5 is a view, similar to Fig. 1, but with an intermediate gear of a different diameter, and

Fig. 6 is an exploded view of the housing showing the details of its construction and certain of the gear supporting means.

The ratio changer shown in the drawings is adapted for use in a recorder to enable the speed of the tape to be varied. The recorder is not shown but it will be appreciated that a ratio changer therefor must be compact and light from the fact that the changer is drawn to approximately twice its actual size. A typical recorder includes a driven shaft 10 in the form of a sleeve through which extends the drive shaft 11.

The ratio changer includes a housing consisting of a base plate 12 provided with a spacer 13 through both of which extend holes to enable the housing to be attached

2

to the recorder or other apparatus by screws. The shafts 10 and 11 extend through the plate 12 and carry gears 14 and 15, respectively.

The base plate 12 is bored to receive a pair of flanged spindles 16. One of these rotatably supports a gear 17 which meshes with an idler gear 18 rotatably mounted on the other spindle 16. The idler 18 meshes with the driven shaft gear 14.

An arm 19 is swingably supported by the shaft 10 and is located between the gear 14 and the base plate 12. The arm 19 is provided with a pin 20 to slidably receive and rotatably support a pair of gears of which the gear 21 is to mesh with the drive shaft gear 15 and the gear 22 is to mesh with gear 17. This pair of gears is coaxial and preferably interconnected as a unit and because they are mounted on the arm 19, they may be moved along an arcuate pathway concentric with the shaft axis. The gear 21, accordingly, remains in mesh with the gear 15 as the arm 19 is swung to carry the gear 22 towards or away from the gear 17 to enable them to intermesh. The gear 22 may be replaced, therefore, by a gear of a different diameter such as the gear 23 as shown in Fig. 5.

It is necessary to provide means to lock the arm 19 against movement when it has been properly positioned. Such means may conveniently consist of a clamping arm 24 recessed as at 25 to receive the free end of the arm 19. The housing includes a cover 26 including a side wall 27 and spacers 28 and 29. The cover 26 is attached to the base plate 12 by screws 30, 31, and 32 with the screw 32 extending through the spacer 28 and one end of the clamping arm 24. The spacer 29 functions to hold the gears 17 and 18 on their spindles.

A screw 33 extends through the center part of the clamping arm 24 and is threaded into the base plate 12 so that by turning it in one direction or the other, the clamping arm 24 is drawn into or released from a position in which the swingable arm 19 is locked against movement. The screw 33 is shown as having a handle 34 and this is disposed so that when the arm 19 is locked against movement, it serves as a retainer to hold the gears on the pin 20. When the screw 33 has been turned to release the clamping arm 24, the handle 34 is positioned to enable the gears supported by the pin 20 to be removed and replaced.

From the foregoing, it will be appreciated that the invention makes possible a gear train in which an intermediate gear may be replaced by one of different diameter to vary the ratio between the drive and driven elements that it connects. With a set of such intermediate gears, a suitable range of gear ratio changes is provided.

What I therefore claim and desire to secure by Letters Patent is:

1. In a ratio changer comprising a gear train including first and second gears, one of which is a driving gear, an arm swingable about the axis of said first gear towards and away from said second gear and including a stud, first and second interconnected coaxial gears of different diameters slidably and rotatably supported by said stud with said first coaxial gear in mesh with said first gear as said arm is swung to enable said second coaxial gear to be positioned in mesh with said second gear, thereby to enable ratio changes to be effected by substituting for said coaxial gear a gear of different diameter, and means to lock said arm against movement when it has been positioned to mesh said second coaxial gear with said second gear, said means including a handle positioned to retain said coaxial gears on said stud when said locking means is operative.
2. A ratio changer to interconnect coaxial driving

and driven shafts and comprising a support through which said shafts extend, an arm swingably mounted on the outer shaft, means carried by said support overlying the free end of said arm and operable to clamp it against said support, a gear train to interconnect said shafts, said gear train including a gear fast on each of said shafts, at least one gear rotatably mounted on said support, and a gear unit, said unit comprising first and second coaxial, interconnected gears of different diameters, said arm including a stud receiving and rotatably supporting said unit with said first gear meshing with one of said shaft gears as said arm is swung towards and away from said support the distance, required by the diameter of said second gear, to effect its meshing with said support mounted gear.

3. A ratio changer to interconnect coaxial driving and driven shafts and comprising a support through which said shafts extend, an arm swingably mounted on the outer shaft, means carried by said support overlying the free end of said arm and operable to clamp it against said support and including an operating screw, a gear train to interconnect said shafts, said gear train including a gear fast on each of said shafts, at least one gear rotatably mounted on said support, and a gear unit, said unit comprising first and second coaxial, interconnected gears of different diameters, said arm including a stud slidably receiving and rotatably supporting said unit with said first gear meshing with one of said shaft gears as said arm is swung towards and away from said support the distance, required by the diameter of said second gear, to effect its meshing with said support mounted gear, said operating screw including a handle disposed to function as a retainer for said unit when said screw has been turned to effect the operative position of said clamping means.

4. In a ratio changer, drive and driven shafts one extending through the other, a gear train interconnecting said shafts to establish a predetermined ratio therebetween, said gear train including drive and driven shaft gears, an intermediate unit comprising first and second interconnected coaxial gears of different diameters of which the first meshes with one shaft gear, and a third gear with which the other shaft gear meshes, means to rotatably support said coaxial gears for movement along

an arcuate pathway concentric with said shafts towards and away from said third gear thus to enable the gear ratio of the train to be varied by substituting for said second coaxial gear a gear of different diameter.

5. In a ratio changer, drive and driven shafts one extending through the other, a gear train interconnecting said shafts to establish a predetermined ratio therebetween, said gear train including drive and driven shaft gears, an intermediate unit comprising first and second interconnected coaxial gears of different diameters of which the first meshes with one shaft gear, and a third gear with which the other shaft gear meshes, an arm, a stud and socket connection between said arm and said unit enabling said unit to be slipped into and out of place therein, said arm being movable along an arcuate pathway concentric with said shafts, thus to enable the gear ratio of the train to be varied by substituting for said second coaxial gear a gear of different diameter, and a keeper pivotally mounted to swing into and out of a position in which it holds said unit on said arm.
6. In a ratio changer, drive and driven shafts one extending through the other, a gear train interconnecting said shafts to establish a predetermined ratio therebetween, said gear train including drive and driven shaft gears, an intermediate unit comprising first and second interconnected coaxial gears of different diameters of which the first meshes with one shaft gear, and a third gear with which the other shaft gear meshes, an arm, a stud and socket connection between said arm and said unit enabling said unit to be slipped into and out of place therein, said arm being swingable to move said connection along an arcuate pathway concentric with said shafts, thus to enable the gear ratio of the train to be varied by substituting for said second coaxial gear a gear of different diameter, means to clamp said arm against movement and including a manually adjustable element engageable with said unit when said arm is clamped to hold said unit on said arm.
